UNITED STATES PATENT OFFICE.

ROBERT G. WESTBROOK AND STEPHEN A. BROWN, OF BIRMINGHAM, ALABAMA.

OUTLET LOCK FOR GASOLINE TANKS.

Application filed September 27, 1926. Serial No. 138,086.

This invention has general reference to means for controlling the withdrawal of the contents of containers, and relates more particularly to such means which is especially adapted for use with the fuel tanks of motor vehicles.

A primary object of the present invention is to produce mechanism by which communication with the interior of a tank or other container, for the withdrawal of the contents thereof, through either the filling opening or the outlet opening, may be controlled by means located within the tank and adapted to be secured against unauthorized operation, as by being locked.

A further object is to provide in connection with such mechanism an improved form of locking means which may be located entirely within the tank, and be adapted for operation with a key from outside the tank.

And a still further object is to provide such locking means, which shall be operable to control simultaneously access to the interior of the tank through the filling opening and access thereto through the draw-off outlet.

The means by which the foregoing and other objects are accomplished by our invention, and the manner of their accomplishment, readily will be understood from the following description on reference to the accompanying drawings, which depict a preferred embodiment of the invention, and in which:

Fig. 1 is a section of a portion of a tank, taken substantially on a line passing through the center of the filling cap opening and that of an outlet opening located at the bottom of the tank.

Fig. 2 is a view of the filling cap and the parts associated therewith, half in top plan, and half in horizontal section on a line passing above the tumblers of the locking mechanism.

Fig. 3 is an enlarged detail view of the lower end of the valve-stem and the valve by which the outlet opening is controlled.

As shown in the drawings, in which corresponding parts are identified by like reference characters throughout the several views, the tank has a top wall 5 and a bottom wall 6, the filling opening being at the top of the tank, and the outlet or draw-off opening being at the bottom. In the filling opening is placed the usual interiorly-threaded bushing 7 into which the filling cap 8 is secured,

the flange 9 of said bushing being welded or otherwise permanently secured to the top of the tank, and the head 10 of the filling cap preferably being hexagonal or of other polygonal configuration, to facilitate placing or removing it with a wrench or other tool.

At the center of the filling cap, a hollow sleeve 11 passes through the top of said cap and is permanently secured thereto, as by welding, said sleeve being interiorly screw-threaded for the reception of a threaded shoulder 12, which forms part of or is rigidly secured to a valve-stem 13 passing loosely through said sleeve axially thereof, said sleeve being screw-threaded at its outer end and having a cap 14 thereon containing packing material 15. At the upper end of the valve stem 13 is secured a hand-wheel 16 by which said stem may be turned. The outlet opening of the tank has a bushing 17 therein, the flange 18 of which is welded or otherwise permanently secured to the bottom of the tank, said bushing having a side opening therein which communicates with a pipe 19 through which the contents of the tank pass therefrom, and a clean-out opening at the outer end of said bushing being normally closed by a screw-plug 20. The inner face of the bushing 17 forms a seat for a conical valve 21 which is carried by the valve-stem 13 at the lower end thereof, the cylindrical shank 22 of said valve being slidable in an opening extending axially of the stem and said shank having a reduced cylindrical portion 23, over which is placed a coiled spring 24, one end of which bears against the inner face of the shank 22, while its other end bears against the top of the opening in the spindle 13. The shank 22 has a slot 25 in one side thereof, and the inner end of a screw 26 is entered in said slot to limit movement of the valve 21 relative to its stem 13.

At the under side of the filler cap 8, alongside the sleeve 11, a segmental block 27 is welded or otherwise permanently secured to said cap, and a hollow sleeve 28 extends through said block, being permanently secured thereto, and is fitted tightly in an opening provided therefor in the top of said cap, the outer end of said sleeve having an end wall which is provided with a key slot 29, and preferably being substantially flush with the top of the cap. At opposite sides of the sleeve 28, parallel slots are formed therein and in the block 27, for the slidable recep-

tion of tumblers 30 and 31, one of which preferably is placed higher than the other, the slot for tumbler 30 being extended through the side wall of the cap 8 and partly 5 through the side wall of the bushing 7, and the slot for tumbler 31 being extended through the side wall of the sleeve 11. The arrangement of said tumblers and said slots is such that the tumblers are held against 10 movement toward or away from the top of the tank, and the width of the extension slot provided for tumbler 30 in the side wall of the cap 8, and that of the extension slot provided for tumbler 31 in the side wall of the 15 sleeve 11, is such as to allow considerable clearance for the tumblers, so as to avoid the necessity for extremely accurate sidewise registration of the tumblers with the respective ones of said extension slots. At one side of 20 each of the slots provided in the block 27 for the tumblers 30 and 31, is a curved flat spring 32, the convex surface of which bears against the side of the tumbler, and one end of which is secured to the block at the side of 25 the slot, while its other end is free to move slidably when the curved portion of the spring is deflected in either direction. The end of the tumbler 31 which is directed toward the valve-stem 13, is bevelled so as 30 to permit said end to be moved close to said valve-stem on a line eccentric to the axis thereof. The tumblers 30 and 31 are provided with slots for the reception of a key 33 by which said tumblers are simultaneously 35 movable slidably to or away from locking position, said key being inserted through the slot 29 at the outer end of the sleeve 28.

From the foregoing description the operation of our improved locking mechanism 40 readily will be understood. To prevent withdrawal of the contents of the tank, either through the filling opening or through the outlet opening, the hand wheel 16 is turned clockwise to screw the valve-stem 13 45 downward, and thus to seat the valve 21 and close the outlet opening in the bushing 17. By means of the key 33 the tumblers 30 and

31 are then moved simultaneously to locking position, with tumbler 30 engaged in the extension slot in the side wall of the cap 8, and 50 tumbler 31 engaged with the top of the threaded shoulder 12 of valve-stem 13. When in said positions, said tumblers prevent either upward movement of the valve-stem 13 to unseat the valve 21, or the unscrewing of the cap 8 to remove it from the filling opening. The slideable movement provided for the valve 21 relative to its stem 22, under action of the spring 24, insures that said valve will be tightly seated until, 55 following movement of the locking tumblers by the key 33, the valve-stem 13 is retracted by contra-clockwise turning of the hand-wheel 16. The principal function of the flat springs 32 is to prevent unintended 60 movement of the locking tumblers, such as might result from vibration or jarring of the tank.

Various modifications of minor details of the improvements disclosed herein doubtless 70 readily will suggest themselves to those skilled in this art, but such modifications fall within the scope of our inventive rights, and our invention is not to be construed as being limited to any details not specifically 75 set out in the claim.

Having thus fully described the invention, what we claim as new, and seek to secure by Letters Patent, is:—

A container having opposed inlet and outlet 80 openings, a removable closure member for the inlet opening, a rigid valve stem carried by the inlet opening closure member and extending into proximity to the outlet opening, a valve yieldingly supported by the 85 stem for closing the outlet opening, and means for simultaneously locking the valve stem and inlet closure when the valve is seated.

In testimony whereof we affix our signatures.

ROBERT G. WESTBROOK.
STEPHEN A. BROWN.
